(57) **CLAIM**

What is claimed is the ornamental design for a crown-shaped panel for a bottle carrier, as shown and described.

DESCRIPTION

The sole FIGURE is a front elevational view of a crown-shaped panel for a bottle carrier.

The boundary of the claimed design is defined by the lines composed of alternating dots and dashes. The dot-dash lines define a boundary such that the claimed design extends to the boundary but does not include the boundary.

The broken lines in the figure are for illustrative purposes only and form no part of the claimed design.
